UNITED STATES PATENT OFFICE

HOWARD E. LEMMERMAN, OF CLEVELAND, OHIO, ASSIGNOR TO THE SIMMONS MANUFACTURING COMPANY, OF CLEVELAND, OHIO, A CORPORATION OF OHIO

VALVE SPRING LIFTER

Application filed June 6, 1931. Serial No. 542,492.

This invention relates to improvements in valve spring lifters and the invention has for its general object the provision of a valve spring lifter which is of improved construction throughout, the present device being simple and inexpensive to manufacture, easy to handle and to operate, of light weight and of compact form, and of exceptionally strong and sturdy construction.

- 10 A specific object of the present invention is the provision of a valve spring lifter in which the valve spring lifting member is operated by suitable toggle members movable into a locked position beyond dead center.
- 15 With the present valve spring lifter, it is therefore possible for a valve spring to be held in raised position without operator effort, both hands of the operator being free for removal from the valve stem of the valve
- 20 spring supporting pin.

Other specific objects of the present invention are in part obvious and in part will appear more in detail hereinafter.

The invention will be readily understood from the following description thereof, reference being had to the accompanying drawing in which

Fig. 1 is a side elevation of the present improved valve spring lifter, with the valve spring lifting member in non-lifting position and with a valve spring assembly shown in dot-dash lines; Fig. 2 is a similar view with the valve spring lifting member locked in lifting position; and Fig. 3 is a top plan view of the present improved valve spring lifter.

The valve spring lifter here illustrated is of metal throughout and includes a suitable handle structure comprising a stationary handle part 1 and a pair of upright links 2 of identical construction and having their lower ends riveted at 3 or otherwise rigidly connected to the handle part 1 on opposite sides thereof. Pivoted at 5 to the upper ends of the links 2 is an ear 6 of a handle member 7, said ear lying between said links, as clearly indicated in Fig. 3. The stationary handle part 1 and the pivotally mounted handle member 7 are preferably

made of pressed steel, of channel shape in cross section and opening inwardly.

Rigidly secured to the front end of the stationary handle part 1 is the rear end of a bearing or supporting part 8 having a depending, transversely disposed front end portion 9. In the embodiment of the invention here shown, said bearing or supporting part 8 is integral with the stationary handle part 1 and said bearing or supporting part, with the exception of the depending front end portion 9 thereof, is of channel shape in cross section and opening inwardly. Pivoted at 12 to the links 2, just in advance of the pivot 5 of the handle member 7, is the rear end of a valve spring lifting member 13 having a horizontally disposed, valve spring engaging jaw 14 at the front end thereof, said jaw being provided with a valve stem receiving slot 15, as is usual in devices of this kind. This valve spring lifting member, with the exception of the jaw 14 thereof, is of channel shape in cross section and opening inwardly, and the rear end of said member lies between the links 2, as clearly shown in Fig. 3.

For moving the valve spring lifting member 13 toward and from the bearing or supporting part 8, suitable toggle mechanism is provided. In the present embodiment of the invention, two pairs of toggle links are used, each pair comprising an upper link 18 and a lower link 19. The two upper links 18 each has its upper end pivotally connected at 21 to the valve spring lifting member 13 intermediate the ends thereof, said links lying on opposite sides of said member. Each of the two lower links 19 has its lower end pivoted at 23 to the bearing or supporting part 8 intermediate the ends thereof, said links lying on opposite sides of said bearing or supporting part. The lower ends of the upper links 18 and the upper ends of the lower links 19 are interconnected at 25 by a suitable pivot pin, to which is connected for operating said links, the front end of a suitable operating member 27.

As indicated in the drawing, the front end of the operating member 27 lies between the two pairs of toggle links 18, 19 and the middle

portion of said operating member extends between the two upright links 2 of the stationary handle structure. The rear end of said operating member is pivoted at 30 to an ear 32 depending from the front end of the pivotally mounted handle member 7.

From the foregoing, it will be apparent that operation of the pivotally mounted handle member 7 effects operation of the operating member 27, the toggle links 18, 19 and the valve spring lifting member 13. Movement of said handle member 7 toward the stationary handle part 1 effects, through the toggle links 18, 19 and their operation member 27, movement of the valve spring lifting member 13 away from the bearing or supporting part 8. Likewise, movement of said handle member 7 away from the stationary handle part 1 effects movement of the valve spring lifting member toward the bearing or supporting part 8.

As indicated in Fig. 2, the toggle links 18, 19 are movable into a locked position slightly beyond dead center, so that the valve spring lifting member 13 can be maintained, without operator effort, in valve spring lifting position, that is, in a position separated or spaced from the bearing or supporting part 8 almost the maximum amount. Movement of the toggle links beyond the self-locking position shown in Fig. 2 is prevented by engagement of the ear or extension 32 with the plate-like supports or links 2, so that the valve spring when lifted will be held without liability of returning to its original position until the handle parts are operated to that end. To move the toggle links from the locked position shown in Fig. 2 to the broken position shown in Fig. 1, it is only necessary to raise the pivotally mounted handle member 7, all as will be readily understood.

In Figs 1 and 2 is shown in dot-dash lines a valve spring assembly within the usual cavity 35 of an engine block. In these two views, 45 36 indicates the top wall of said cavity and 37 indicates the bottom wall thereof. Extending through a suitable opening in the cavity top wall 36 is an upright valve stem 38 surrounding which is a valve spring 40, the lifting of which is the function of the present device. The upper end of said spring engages the cavity top wall 36 while the lower end of said spring seats upon a suitable capped washer 41 which in turn seats upon a cross pin 43 removably secured in a transverse opening in the lower end of the valve stem 38.

In order to remove the valve stem 38 from the engine block for valve grinding purposes, it is necessary that the pin 43 be removed from said stem. In order to remove said pin, it is necessary to raise the valve spring 40, as in Fig. 2. To lift said spring, the jaw 14 of the valve spring lifting member 13 of the present device is inserted between the capped washer 41 and the cross pin 43, the valve stem 38 en-

tering the slot 15 of said jaw. The depending front end portion 9 of the bearing or supporting part 8 is positioned on top of the cavity top wall 37, as shown in Figs. 1 and 2, and forms a bearing or support for the device. 70 The jaw 14 of the valve spring lifting member 13 is positioned beneath the valve spring 40 with the parts of the present valve spring lifter in the position shown in Fig. 1, that is, with the toggle links 18, 19 in broken condition. The operator then depresses the pivotally mounted handle member 7, which effects a straightening of the toggle links 18, 19 with consequent raising of the valve spring lifting member 13 and the valve spring 40 above the 80 jaw 14 thereof. The operator depresses the pivotally mounted handle member 7 a sufficient amount to move the toggle links 18, 19 into a locked position beyond dead center, as shown in Fig. 2. The valve spring lifting member 13 and the valve spring 40 are thereupon maintained in lifted position without operator effort, so that both hands of the operator are free for use in the withdrawal from the valve stem 38 of the cross pin 43. 90

After said cross pin has been removed, the operator simply raises the pivotally mounted handle member 7, which effects a breaking of the toggle links 18, 19 and a lowering of the valve spring lifting member 13 and the valve 95 spring 40. The valve stem 38 can then be lifted from the engine block.

What I claim is:

A valve spring lifter, comprising a rigid member having bearing and handle portions 100 at its opposite ends and between them a pair of laterally extending plate-like supports each provided with an ear, said supports lying side by side in spaced parallel planes, a lifting jaw pivoted between said supports and 105 extending opposite said bearing portion, toggle members connecting said bearing portion and jaw, an operating handle pivoted between said ears and having an extension toward the first named handle portion, and a 110 link connecting said extension to the toggle members and passing between said supports, the supports and extension being so formed and arranged and the link being of such length that on closing the handles the toggle 115 members move beyond dead center and the extension abuts said supports to limit such movement to a self-locking position.

In testimony whereof I hereby affix my 120 signature.

HOWARD E. LEMMERMAN.
